**SELECTIVE SOLVENT EXTRACTION PROCESS
IN THE GAS-OIL RANGE**

Charles J. Norton, Denver, Colo., assignor to Marathon
Oil Company, a corporation of Ohio
No Drawing. Filed Mar. 28, 1960, Ser. No. 17,786
4 Claims. (Cl. 208—314)

There are many selective solvents for the extraction of specific hydrocarbon components from various hydrocarbon systems, especially in the petroleum industry, and it is obvious that there is no one selective solvent which is adequate for all purposes. In using a selective solvent for the extraction of certain hydrocarbons components from hydrocarbon mixtures, there are several different systems for the subsequent separation of the solvent from the extracted hydrocarbon. In one system, for example, extracted aromatic hydrocarbon is removed from the selective solvent by water washing, sometimes known as springing. In another system, the extracted hydrocarbon may be removed from the selective solvent by distillation. Where it is possible to use an atmospheric distillation, when the character of both the selective solvent and the aromatic hydrocarbon being extracted permits such a distillation, this is generally a desired procedure since it is economical and both components are recovered in a dry state. With certain selective solvents the water springing is impossible since the solvent decomposes in the water. Such decomposition not only destroys the selective solvent but the reaction products may contaminate the hydrocarbon fraction extracted.

One commonly used selective solvent is gamma-butyrolactone, which may be used with or without water, showing a certain selectivity for aromatics from hydrocarbon mixtures, among other systems. Gamma-butyrolactone has a boiling point of about 204° C. which makes direct distillation of it from an aromatic extract in the gas-oil range impractical. Thus when using the gamma-butyrolactone to extract aromatic hydrocarbons from many hydrocarbon feeds, the gamma-butyrolactone must be washed with water or other "antisolvent" from the aromatic hydrocarbon. This, obviously, introduces a still further component into the system since the solvent is not simply recovered completely dry or completely free of the antisolvent. Many other solvents have been proposed in various systems, but in only a few instances are there any selective solvents which boil out of the gas-oil range and which will provide sufficient extraction for an economical system.

In one of the embodiments of the invention, beta-propiolactone has been found useful as a selective solvent for removing aromatic hydrocarbons from nonaromatic hydrocarbons in the gas-oil range. Furthermore, substituted beta-propiolactones and beta-propiolactams of the general formula

wherein Y is selected from the class consisting of O and N—R₂; R₂ is selected from the class consisting of H and lower alkyl groups of from C₁ to C₅; and R₁ is selected from the class consisting of hydrogen, halogen, nitrite, amine, and lower alkyl groups of from C₁ to C₅; are useful for selectively removing aromatic hydrocarbons from nonaromatic hydrocarbons.

An important object of the invention is to provide the separation of one class of hydrocarbons from different classes of hydrocarbons by means of certain beta-propiolactones and beta-propiolactams. A further object of the invention is to provide a separation of aromatic

2

hydrocarbons from gasoline boiling range aromatic and nonaromatic hydrocarbon mixtures.

It is a further object of the invention to provide a cyclic process for the separation of aromatic hydrocarbons in the gasoline boiling range aromatic and nonaromatic hydrocarbon feeds.

These and other objects and advantages of the invention may be accomplished by selective solvent extraction of a mixture of aromatic and nonaromatic hydrocarbons with a selective solvent selected from the class of beta-propiolactones and beta-propiolactams, which are cyclic compounds formed from certain beta-hydroxy and beta-amino acids.

In practice the hydrocarbon mixture containing the aromatic and nonaromatic hydrocarbons is thoroughly admixed with the desired selective solvent by any suitable means, as for example, mechanical agitation or in a countercurrent extraction column. On settling the two immiscible phases which are formed are then separated. The upper or raffinate phase has an appreciably reduced content of the aromatic hydrocarbons and the lower layer or phase contains the major amount of selective solvent which is substantially enriched in the aromatic hydrocarbons from the feed and a limited amount of nonaromatic hydrocarbons. The raffinate may be recovered by washing with a small amount of water or distillation to remove residual amounts of the solvent dissolved therein. The extract phase may then be atmospherically distilled to recover the aromatic free from the solvent. The recovered solvent may then be used for subsequent extractions in a cyclic process. In modified procedure the extract phase may be washed with another hydrocarbon feed mixture, which is in a different boiling range, to provide a raffinate containing the aromatic hydrocarbon from the first feed mixture and which was originally dissolved in the solvent. This raffinate is readily separated by atmospheric distillation. The aromatic hydrocarbon from the second feed (now dissolved in the solvent) has replaced the original aromatic hydrocarbon mixture in the solvent, and it may then be recovered by distillation from the solvent or by mass action of an additional treatment with more of the original gasoline boiling range hydrocarbon mixture.

Following the latter mentioned procedure, a cyclic process may be derived wherein the hydrocarbon in the gasoline boiling range is initially passed through the selective solvent until the selective solvent is essentially saturated with the aromatic hydrocarbons. Then a mixture of hydrocarbons in a different boiling range may be passed through the aromatic-solvent mixture so that the aromatic hydrocarbons in the second hydrocarbon feed replace the aromatic hydrocarbons dissolved in the solvent until the aromatics from the second feed essentially saturate the selective solvent. The feed mixtures are passed through the solvent phase until the aromatics in the incoming feed replaces the aromatics dissolved in the solvent. By alternately passing these feeds through the solvent, a cyclic process is provided wherein two different raffinates may be recovered each of which contains aromatics in a different boiling range. This provides a system in which the aromatics are readily separated from the nonaromatics and recovered by a simple distillation process. In such processes it may be necessary to add small amounts of the selective solvent to replace the selective solvent dissolved in the raffinate leaving the system.

Example I

A portion of beta-propiolactone was shaken with a 50-50 toluene-n-heptane mixture having refractive index of n_D^{20} 1.4400 at a two to one oil-to-solvent ratio. The recovered raffinate, which is the solvent lean phase, was

recovered from an extract (which is an aromatic rich solvent phase). On washing the raffinate with water to remove the solvent from both of these phases, the following products were obtained, and the composition of these are indicated from refractive index curve of known mixtures of the two, as is well known procedure:

	Vol. per- cent of Mixture	n_{D}^{20}	Vol. per- cent Aro- matics
Raffinate.....	74.3	1.4278	38.7
Aromatic Extract.....	25.7	1.4748	81.0

The solvent, however, has a boiling point which is essentially within the gasoline boiling range, that is about 162° C. The solvent, therefore, may not be recovered from the aromatics by direct distillation, but the mass action principle of exchange may be applied wherein a hydrocarbon mixture in a different boiling range may be passed through the aromatic-solvent mixture so as to replace the aromatic dissolved in the solvent with the aromatic in the second feed.

Example II

A portion of beta-propiolactone was shaken with a reformate having a refractive index of n_{D}^{20} 1.4542 at a two to 1 oil-to-solvent ratio. The primary raffinate, that is the solvent-lean phase, and a primary extract phase, that is the solvent-rich phase, were separated. On washing the samples of these phases with water to remove the solvent, the following products were obtained:

	Vol. per- cent of Reformate	n_{D}^{20}
Primary Raffinate.....	89.2	1.4496
Primary Aromatic Extract.....	10.8	1.4921

Example III

If the primary extract obtained from Example II is shaken with a light catalytic cycle oil at about a one to two primary extract phase to light catalytic cycle oil, a secondary raffinate and a secondary extract phase result. On washing these two phases with water to remove the solvent from the phases, the following products were obtained:

	n_{D}^{20}
Secondary raffinate.....	1.5000
Secondary aromatic extract.....	1.5570

When refractive indices of these aromatic extracts are compared, it is apparent that the gasoline range aromatics may be displaced from an extract phase by higher boiling aromatics from a gas-oil hydrocarbon mixture. After the exchange has occurred, the low boiling aromatics which are then in secondary raffinate (along with higher boiling nonaromatics) may be removed by direct distillation. The low boiling aromatics are recovered as the overhead, and solvent may be recovered from the secondary extract phase by direct distillation.

Example IV

A portion of beta-propiolactone solvent is shaken with a light catalytic cycle oil (LCCO) in a ratio of about 2.5 to 1 volume of oil-to-solvent and raffinate and extract phases result. The two phases were separated and on washing with water to remove the solvent from these phases the following products were obtained:

	Volume of LCCO	n_{D}^{20}
Raffinate.....	88	1.4990
Aromatic Extract.....	12	1.5988

When a similar amount of light catalytic cycle oil is shaken in a ratio of 2.5 to 1 oil-to-solvent ratio with gamma-butyrolactone, the following results:

	Volume of LCCO	n_{D}^{25}
Raffinate.....	79	1.4916
Aromatic Extract.....	22	1.5795

When the light catalytic cycle oil is extracted with a 2.5 to 1 oil-to-solvent ratio of 95% aqueous gamma-butyrolactone, however, the following results:

	Volume of LCCO	n_{D}^{25}
Raffinate.....	88	1.5013
Aromatic Extract.....	12	1.5892

From these results it is readily seen that the beta-propiolactone is far superior to either gamma-butyrolactone or the aqueous gamma-butyrolactone in its selectivity for the aromatics. While its capacity is essentially the same as 95% aqueous gamma-butyrolactone, it is superior in its selectivity of the aromatics. Further, the beta-propiolactone boils at 162° making direct distillation from the extract phase feasible. On the other hand the gamma-butyrolactone boils at 204° C. and therefore must be washed from the extract with water.

I claim:

1. A process of obtaining an extract rich in aromatic hydrocarbons from a mixture of aromatic and non-aromatic hydrocarbons by means of a phase separation comprising extracting said hydrocarbon mixture with beta-propiolactone, and separating the aromatic rich extract phase from the raffinate phase.

2. A process of obtaining an extract rich in aromatic hydrocarbons from a mixture of aromatic and non-aromatic hydrocarbons in the gas-oil range by means of a phase separation, comprising extracting said hydrocarbon mixture with beta-propiolactone as the selective solvent, and then separating the aromatic rich extract phase from the raffinate phase.

3. A process for obtaining an extract rich in aromatics from a mixture of aromatic and non-aromatic hydrocarbons in the gas-oil range by means of a phase separation comprising extracting said hydrocarbon mixture with about a 2 to 1 oil-to-solvent ratio of beta-propiolactone as a solvent, and then separating the aromatic rich solvent phase from the raffinate phase.

4. A process of obtaining an extract rich in aromatics from a mixture of aromatic and non-aromatic hydrocarbons in the gas-oil boiling range comprising extracting said hydrocarbon mixture having a first boiling range with beta-propiolactone as the selective solvent to form an extract rich in the aromatics in the gas-oil boiling range, extracting the resultant aromatic-rich solvent phase by adding a mixture of aromatic and non-aromatic hydrocarbons in a second boiling range different from boiling range of said gas-oil hydrocarbon mixture to thereby replace the aromatics of the gas-oil range dissolved in the solvent, and then distilling the resultant mixture containing aromatics from the gas-oil range mixture and the non-aromatics from the different boiling range mixture to thereby recover the gas-oil aromatics.
